SHOE TAP

Phillip Kurkjian, Selma, and Edward J. Derderian, Fresno, Calif.

Application October 13, 1950, Serial No. 190,032

4 Claims. (Cl. 36—8.3)

1

The present invention relates to shoe taps and more particularly to the combination of a hollow tap enclosing a clapper productive of novel sound effects.

Dance taps for attachment to dance shoes for creating rhythmic effects in tap dancing are well known. These taps have conventionally been made of a single piece of sheet or cast metal formed in such a manner that when attached to dance shoes and tapped on the floor, as in tap dancing, cause a desired clacking or clicking sound. There has been developed a technique in tap dancing in which it is desirable for the taps to provide additional clacking sounds independent of the striking of the taps on the floor.

It is an object of the present invention to provide an improved dance tap which is adapted to the production of such additional or auxiliary sounds.

Another object is to provide a dance tap embodying rattling members which produce clacking sounds on oscillative motion of the feet of a performer employing the same.

Another object is to provide a dance tap in which additional rhythmic effects can be obtained over the conventional one piece taps heretofore used on tap dance shoes.

Another object is to provide dance taps productive of clacking sounds independent of floor contact.

A further object is to provide in a shoe tap having a circular chamber, clapper members in the chamber of geometric shapes precluding non-clapping rotation of the members in the chamber.

Still further objects and advantages will become apparent in the subsequent description in the specification.

In the drawings:

Figure 1 is a perspective view of a shoe provided with a dance tap of the construction of the present invention.

Figure 2 is a fragmentary, somewhat enlarged bottom plan view of the shoe and the dance tap attached to the heel thereof.

Figure 3 is a vertical fragmentary longitudinal section through the portion of the shoe and dance tap shown in Figure 2, as taken along line 3—3 thereof.

Figure 4 is an exploded perspective view illustrating the various members of the dance tap of the present invention.

Referring in greater details to the drawing:

In Figure 1 of the drawing is illustrated a shoe, indicated generally by the reference numeral 10,

2

having a heel 11 to which a dance tap of the present invention is attached. The heel is recessed upwardly from its lower surface with a cylindrical bore 12 having a shallow counter-recess 13, the counter-recess 13 preferably opens to the outer edge of the heel of the shoe. In instances in which the heel is composed of rubber, the recess 12 and counter-recess 13 are molded as the heel is originally formed, and when the heel is of leather composition, the recess 12 and counter-recess 13 may be cut from the layers or laminations of leather forming the heel.

The dance tap of the present invention is indicated generally by the reference numeral 15 and includes a cup 16 conveniently stamped from a piece of sheet metal, cast, or otherwise formed. The cup is provided with a circular upper end portion 17, an integral cylindrical side portion 18, and an integral radially extended flange 19. The cup 16 is slightly shallower than the depth of the recess 12 and the cylindrical side portion 18 thereof is of slightly smaller outer diameter than the diameter of the recess 12 so that when the cup is inserted in the recess 12, the bottom and cylindrical side of the cup may be spaced from the bottom and sides of the recess. The flange 19 of the cup 16 is fitted to the counter-recess 13 and provided with a plurality of perforations 20 therethrough for attachment of the cup interiorly of the recess 12 as hereinafter more fully described. This flange is preferably formed with an arcuate edge 21 to fit the contour of the heel of the shoe.

A sheet metal cover plate 24, substantially congruent to the peripheral extremities of the flange 19 is located against the flange 19 and together the flange and plate are positioned in the counter-recess 13. The counter-recess is formed to a depth to receive the flange 19 and contacting cover plate 24 with the outer surface of the cover plate substantially flush with the lower surface of the heel 11. The cover plate 24 is provided with a plurality of perforations 25 therethrough aligned with the perforations 20 on the flange 19 so that nails 26, screws, or the like may be passed through the perforations 25 and 20 and into the heel 11 of the shoe to hold the cover plate securely to the flange 19 and to hold the cup 16 securely in the recess 12 in spaced relation to the sides and bottom thereof. The cover plate is formed with an arcuate edge 27 identical to the arcuate edge 21 on the flange 18 to conform with the heel periphery.

The cup 16 and cover plate 24 constitute a housing adapted to enclose a spherical clapper

29 and a cylindrical clapper 30 therein. It will be observed that the upper end portion 17 and the cylindrical side portions 18 of the cup 16 in association with the flange 19 define a shallow cylindrical housing for the clappers 29 and 30. Although the present invention is not restricted to such cylindrical form, it has been discovered that this form imparts uniformity of timing to the device independent of direction of shoe movement. A problem in shoe taps of the type described, is that of circular rolling or skidding of the clappers employed around the cylindrical walls of the portion 18. When so moving, the clappers fail to perform their intended functions. This lack of dependability is obviously intolerable in such a structure and is successfully overcome by employment of a spherical and a cylindrical clapper. A spherical clapper, when employed alone, frequently has imparted thereto a circular rolling movement. A cylindrical clapper, when employed alone, frequently has imparted thereto a circular sliding movement. The coaction of the cylindrical clapper 30 and the spherical clapper 29 in the cylindrical chamber provided therefor obviates such circular movement and assures uniform operation. Circular rolling of the member 29 is precluded by the cylindrical clapper and any extensive circular sliding of the cylindrical clapper precluded by the striking of the spherical clapper thereagainst.

Operation

With the dance tap 15 attached to a heel of a shoe as shown and described, the tap is ready for use in producing additional rhythmic sounds in a tap dance. The cup 16, being located within the recess 12 in spaced relation thereto, and the cover plate 24 located over the cup 16 provide a vibratory sound chamber for the clacking sounds made by the clappers 29 and 30 as they strike the cylindrical side of the cup. The joint mounting of the cup and cover plate and their abutting relationship causes the plate to act as a sounding board.

The combination of a ball clapper 29 and cylindrical clapper 30 is provided for more effective operation of the dance tap in creating audible clicking sounds. Their coaction precludes non-clacking rotation thereof around the inner periphery of the cylindrical side portion 18, as previously described.

The extension of the plate 24 to the edge of the heel 11 and the provision of arcuate edges 21 and 27 on the flange 19 and cover plate 24, respectively, at the edge of the heel permits the direct striking of the device of the present invention on the floor when desired. It is further to be observed that the edge 27 provides the wear resisting function of a heel plate.

Although we have herein shown and described our invention in what we have conceived to be the most practical and preferred embodiment, it is recognized that departures may be made therefrom within the scope of our invention, which is not to be limited to the details disclosed herein, but is to be accorded the full scope of the claims so as to embrace any and all equivalent devices and structures.

Having described our invention, what we claim as new and desire to secure by Letters Patent is:

1. A shoe tap comprising a metallic cylindrical cup having a closed end and an open end, a radially extended flange integral with the cup in circumscribing relation to the open end of the cup adapted to mount said cup in spaced

relation to the walls and bottom of a recess formed in a shoe, a metallic cover plate substantially congruent to the flange mounted in covering relation to the cup and therewith defining a housing, a spherical clapper loosely enclosed by the housing, and a cylindrical clapper loosely enclosed by the housing, said clappers having diameters appreciably less than the spacing of the closed end of the cup and the cover plate.

2. In combination with a shoe having a cylindrical recess in the heel thereof, a cylindrical metallic cup of a diameter less than the diameter of the recess and a length less than the axial length of said recess having a closed axial end and an open opposite end, a flange radially extended in circumscribing relation from the open end of the cup, a cover plate substantially congruent to the flange arranged in covering relation to the cup and therewith defining a housing, a spherical clapper loosely enclosed in the cup by the plate, a cylindrical clapper loosely enclosed in the cup by the plate, and means extended through the plate and flange into the shoe mounting the cup within the recess in spaced relation to the sides and end thereof with the plate substantially flush with the lower surface of the heel of the shoe.

3. In combination with a shoe having a recess formed in the bottom thereof defined by circumscribing walls and a bottom; a metallic cup having circumscribing side walls, a closed end, an open end, and a radially extended flange integral with the cup in circumscribing relation to the open end of the cup; a metallic cover plate substantially congruent to the flange positioned in covering relation to the cup and therewith defining a housing; means passed through the cover plate and the flange engaged in the shoe mounting the cup in the recess with the walls of the cup in spaced relation to the walls of the recess and the closed end of the cup in spaced relation to the bottom of the recess; and a clapper loosely enclosed in the housing.

4. In combination with a shoe having a recess formed in the bottom thereof defined by circumscribing walls and a bottom; a metallic cup having circumscribing side walls, a closed end, an open end, and a radially extended flange integral with the cup in circumscribing relation to the open end of the cup; a metallic cover plate substantially congruent to the flange positioned in covering relation to the cup and therewith defining a housing; means passed through the cover plate and the flange engaged in the shoe mounting the cup in the recess with the walls of the cup in spaced relation to the walls of the recess and the closed end of the cup in spaced relation to the bottom of the recess; a spherical clapper loosely enclosed by the housing; and a cylindrical clapper loosely enclosed by the housing, said clappers having diameters less than the spacing of the closed end of the cup and the cover plate.
